UNITED STATES PATENT OFFICE.

ALEXANDER CONSTANTINE IONIDES, JR., OF LONDON, ENGLAND.

DEVICE FOR OBTAINING A CONSTANT MIXTURE OF TWO ELASTIC FLUIDS.

1,095,871.

Specification of Letters Patent.

Patented May 5, 1914.

Application filed September 3, 1912. Serial No. 718,372.

To all whom it may concern:

Be it known that I, ALEXANDER CONSTANTINE IONIDES, Jr., a subject of the King of Great Britain and Ireland, and residing at 534 Porchester Terrace, London, W., England, have invented a certain new and useful Improved Device for Obtaining a Constant Mixture of Two Elastic Fluids, of which the following is a specification.

10 This invention relates to apparatus for obtaining a constant mixture of two elastic fluids such as gas and air, and particularly to that of the type in which a member controls simultaneously the valves by which the pressure of the two fluids is regulated. In such apparatus as has hitherto been proposed, the constant mixture is obtained by reducing both fluids to the same pressure. As a result of the loss in pressure energy thus incurred, the apparatus is unsuitable in cases where there is a large difference between the pressure of the two fluids.

25 The object of the present invention is to overcome this disadvantage, and to provide an apparatus by which a mixture of any strength can be maintained constant independently of variations in the rate at which the mixture is consumed.

30 The invention consists in an apparatus of the above type in which the valve controlling member is maintained in equilibrium by being subjected to the static part of the regulated pressure of one fluid acting thereon in opposition to the static part of 35 the regulated pressure of the other fluid, whereby on applying an unbalanced force to said member the strength of the mixture is varied as desired.

40 The invention also consists in the apparatus hereinafter described for obtaining a constant mixture of two elastic fluids.

45 Referring now to the accompanying drawings:—Figures 1 and 2 show in vertical section and in plan respectively one form 50 of the apparatus according to the present invention. Figs. 2^a and 2^b are vertical sections of the regulating valves, 3 and 5, shown in Fig. 2. Fig. 3 is an outside elevation of another form of regulating apparatus according to the present invention. Fig. 4 is a vertical section on the line, A—A, of the apparatus shown in Fig. 3. Fig. 5 is a vertical section on the line B—B, of Fig. 4. Fig. 6 is a horizontal section on the line C—C, of Fig. 3. Figs. 7 and 8 show in elevation details of the gas and air valves used

in the apparatus illustrated in the preceding figures numbered 3 to 6 inclusive, and Fig. 9 is a view similar to Fig. 4, showing on an enlarged scale one side of the device shown in Fig. 4.

One form of an apparatus according to the present invention is shown in Figs. 1 and 2, for obtaining a constant proportion mixture of coal gas and air. The gas passes to a mixing chamber, 1, by way of a conduit, 2, controlled by a valve, 3, while the air is supplied by a conduit, 4, controlled by the valve, 5. The gas and air valves, 3 and 5 respectively, are of any suitable type so long as they offer a minimum resistance to operation. As shown by way of example in Figs. 2^a and 2^b, such valves are of the disk type in which slides, 3^a and 5^a control valve openings, 3^b and 5^b respectively, such openings being arranged as shown with respect to one another, so that when one valve is closing the other is opening. The slides, 3^a and 5^a, of these valves are connected to a spindle, 6, which passes through the side walls of a metal tank, 7, containing liquid up to a level, a, a; suitable bearings and packings being provided at the place where the spindle, 6, passes through the tank walls. Upon the spindle, 6, there is mounted a member hereinafter known as a bell chamber, which consists in a metal casing, 8, enclosing a chamber, 9, which is sealed by the liquid in the tank.

To the chamber, 9, gas is admitted through a conduit, 10, which passes through the tank wall and branches from the main gas conduit, 2, on the outlet side of the gas regulating valve, 3. As the gas thus admitted to the bell chamber, 9, cannot pass out therefrom, the internal surface of the casing, 8, is subjected to the static pressure of the gas in the conduit, 2, and is thus unaffected by any pressure arising from the velocity with which the gas is passing through the conduit, 2. In a similar way the external surface of the casing, 8, is subjected to the static pressure of the air in the main air conduit, 4, which is in communication with the space, 11, above the liquid level, a, a, by means of another conduit, 12, branching from the air conduit, 4, on the outlet side of the air regulating valve, 5.

The bell chamber is suitably counterbalanced for example by levers, 13, which at one end are secured to the spindle, 6, carrying the bell chamber, and at the other end

connected together by a rod, 14, to which is attached a cord passing over a pulley, 15, and carrying the required weight, 16. As the weight, 16, balances the difference between the oppositely acting forces on the casing, 8, due to the gas and air pressures thereon, equilibrium only exists for a certain ratio between such pressures which ratio can be varied at will by altering the weight, 16.

10 Any variation in the pressure of the gas or air effects a slight angular movement of the casing, 8, until equilibrium is restored by the inverse operation of the valves, 3 and 5. The ratio between the pressure of the gas inside and that of the air outside the casing, 8, being thus maintained constant a mixture of gas and air in the desired constant proportions passes to the mixing chamber, 1, and that in spite of variation in the 20 pressure of supply of each gas or in the rate of consumption of the mixture.

Instead of the bell chamber casing, 8, being balanced by an external system of forces, the balance may be effected by providing a 25 second bell chamber casing mounted upon the same spindle as the first casing and arranged diametrically opposite thereto, each of said casings being placed in separate chambers and subjected internally to the 30 static pressure of the fluid to which the external surface of the other casing is subjected. Such an arrangement is shown by way of example in Figs. 3 to 8 in which the regulating apparatus consists in a suitably 35 supported tank, 17, which is filled with a liquid such as oil, up to the level, a , a , and is closed by a lid, 18, which extends below said liquid level. The lid, 18, carries a partition wall, 19, which projecting below the 40 liquid level, divides the space above the liquid into two separate chambers, 20 and 21, in which are situated the bell chamber casings. The latter have, according to the form illustrated, side walls, 22, consisting of 45 circular metal disks rigidly attached to a hollow spindle, 23, which runs on suitable ball bearings, 24, placed between itself and a spindle, 25. Walls, 26, extending radially outward from the spindle, 23, and circumferentially around the edge of said disks contact with the sealing liquid to form segmental bell chambers, 27 and 28, which are situated in the chambers 20 and 21 respectively.

Branching from the main air conduit is a 55 pipe, 29, which passes through the wall of the tank, 17, and projects above the liquid level, a , a , therein, whereby the inner surface of the bell chamber, 27, is subjected to the static pressure of the air flowing in the main 60 air conduit. A similar pipe, 30, causes the internal surface of the bell chamber, 28, to be subjected to the static pressure of the gas in the main gas conduit, while further pipe connections, 31 and 32, place the chambers, 20 and 21, in communication with the

gas and air conduits respectively. Instead, however, of placing the main air and gas valves and the pipe connections from the regulator thereto entirely outside the regulator as in the previous form of the device, the casings, 33 and 34, of the gas and air valves respectively are attached on each side of the tank casing, 17, and lid, 18, the chamber within each of these casings being divided into two compartments by plates, 35 and 36. To the compartment between the plate, 35, and the tank wall gas is admitted from the main conduit, 37, and passes by way of an opening, 38, in the plate, 35, into the compartment on the outer side of said plate and thereafter into the conduit, 39, leading to the mixing chamber, 1. In a similar manner the air flowing in the main air conduit, 40, passes into the compartment between the plate, 36, and the adjacent tank wall and from thence by way of an opening, 41, in the plate, 36, to the conduit, 42, which also leads to the mixing chamber.

As the quantity of gas and air passing in the main conduits will thus depend upon the area of the openings, 38 and 41, in the plates, 35 and 36, respectively, means are provided by which such area is varied directly in accordance with the movement of the bell chambers. According to one construction 95 the spindle, 23, on which the bell chambers are secured carries two cranks, 43 and 44, capable of angular movement within separate chambers, 45 and 46, which are sealed by the liquid in the tank, the bell chamber casings being as shown of such a shape that their movement is unaffected by the crank chambers.

Openings 47 and 48 in the tank walls and lid allow the cranks 43 and 44 to engage respectively with slides, 49 and 50, which in moving vary the area of the openings, 38 and 41, in the plates, 35 and 36, in the gas and air valves. Each of the valve slides, 49 and 50, is carried by arms, 51, which are attached to a central boss, 52, that belonging to the gas valve being rotatable about a suitable pivot fixed in the plate, 35, while that belonging to the air valve is rigidly mounted upon a similar pivot which, however, is movable relatively to the plate, 36. The slides, 49 and 50, are as shown in Figs. 7 and 8, preferably connected to the two arms, 51, by hinges, 53, the axes of which are in line with one another whereby the slides always lie flat on their respective valve plates.

By arranging the one slide diametrically opposite the other in the manner shown in Figs. 7 and 8, in which the crank, 43 engages with a rod, 54, attached to the rotatable boss, 52, while the crank, 44, engages directly with the valve slide 50, it will be seen that the weight of one valve slide will be exactly balanced by that of the other. The valve slides, 49 and 50, having been thus 130

arranged, the plates, 35 and 36 are placed so that the openings, 38 and 41, therein are in the position shown in Figs. 7 and 8 with respect to one another, so that when one valve 5 slide such as the gas valve slide, 49, is moving in a clockwise direction, the opening, 38, is being uncovered while the air valve slide 50, in moving in the same direction, is closing the opening, 41, in the plate, 36.

10 With the main air and gas valves formed and arranged in the above manner, it has been found that they offer a minimum resistance to operation and since the fluid pressure is acting upon the back of the valve slides, the 15 slides are always maintained in close contact with the valve plates whereby leakage of the fluid through the valve is avoided. The gas and air having passed through the main valve is conducted by the conduits, 39 and 20 42, into separate chambers, 55 and 56, and from thence by way of openings, 57 and 58, into the mixing chamber, 1, the latter being if desired attached to the outer walls of the regulator. The openings, 57 and 58, are 25 controlled by suitable valves which may as shown comprise sliding plates 59 and 60, each of which is provided with a toothed rack engaging with pinions 61 and 62 which are mounted upon shafts capable of being 30 rotated independently from the exterior of the mixing chamber, say by means of a milled head, 63. In this way the valve slides, 59 and 60, can be adjusted to allow the gas and air to pass to the mixing chamber 35 in any desired proportions.

In order to prevent the gaseous mixture returning to the conduits, 39 and 42, the 40 openings, 57 and 58, are further controlled by non-return valves of any type such as that illustrated, in which each is provided with a plate, 64, suspended in such a manner that the valve remains closed either when there is a back pressure in the system or no gas or air flow. The static connections 45 for the gas and air now branch directly from the valves controlling said fluids; that is, the pipe connections, 30 and 29, by which the interior of the bell chambers 27 and 28 is subjected to the static pressure of the gas and 50 air respectively are connected to the respective valve compartments between the plates, 35, 36 and the valve casing walls, 33, 34, while from these compartments there branch the pipe connections, 31 and 32, by 55 which gas and air are respectively admitted to the chambers, 20 and 21. In this way there is obtained an exceedingly compact arrangement of the various valves and pipe connections, which latter are thus less liable 60 to injury when in use or during transit.

In using an apparatus of this kind the valves 59 and 60 are first adjusted so that the area of the openings, 57 and 58 will allow gas and air to pass to the mixing 65 chamber in the desired proportions. If now

for any reason the gas pressure in the mains for example increases, the bell chambers will as can be seen from Fig. 5, move about the spindle 25 in an anti-clockwise direction and thereby effect a closing of the main gas 70 valve and at the same time an opening of the main air valve. If on the other hand there is a decrease in the pressure at which the gas is supplied the bell chambers will move in a clockwise direction, and thereby open 75 the gas regulating valve and at the same time close the air regulating valve, while if the pressure of the air vary, the regulating valves will be automatically adjusted until the equilibrium of the bell chambers is re- 80 stored, under which condition the ratio between the pressure of the gas and that of the air is always constant. A mixture of gas and air in constant proportions is thus obtained in spite of variation in the pressure 85 of supply of either constituent, or of fluctuations in the rate of consumption of the mixture.

Obviously the difference between the pressures of the two fluids in such an apparatus 90 can be varied as desired by simply weight- ing the respective gas or air bell chamber casings. For example, to enable the gas to be used at a greater pressure than the air, the bell chamber to which gas is admitted 95 is acted upon by a force having a constant moment about the axis of the spindle, 23, this being effected as indicated in Fig. 9, by attaching a suitable weight, 65, by means of a cord, 66, to a pulley, 67, which is rigidly 100 mounted upon the pivot, 68, carrying the boss, 52, and arms, 51, by which the torque produced by the weight is transmitted to the bell chamber casings.

By employing a plurality of apparatus 105 according to the present invention, a constant strength mixture of any number of fluids can be obtained.

Obviously, the bell chamber within the tank may be constructed in many ways pro- 110 vided that in combination with a liquid seal it is capable of producing separate cham- bers or compartments for the separate fluids which afterward constitute the fluid mix- ture.

Having now described my invention what I claim as new and desire to secure by Letters Patent is:—

1. An apparatus for obtaining a constant mixture of two elastic fluids, comprising in 120 combination a member simultaneously regulating the pressure of each fluid, said mem- ber being maintained in equilibrium by the static part of the regulated pressure of one fluid acting thereon in opposition to the 125 static part of the regulated pressure of the other fluid, and means for applying a force of variable magnitude to said member whereby the ratio existing between the pres- 130 sure of the two fluids when the member is

in equilibrium can be varied, and a constant mixture of any desired strength thereby continuously produced.

2. An apparatus for obtaining a constant mixture of two elastic fluids comprising in combination a separate valve for regulating the pressure of each fluid, a member connected to said valves, and operating the latter inversely with respect to one another, 10 said member being maintained in equilibrium by the static part of the regulated pressure of one fluid acting in opposition thereto to the static part of the regulated pressure of the other fluid, and means for 15 applying a force to said member to vary the ratio existing between the pressure of the two fluids when the member is in equilibrium, whereby a constant mixture of any desired strength is continuously produced.
3. An apparatus for obtaining a constant mixture of two elastic fluids comprising in combination a separate valve for regulating the pressure of each fluid, bell chamber means connected with said valves to control 25 the latter simultaneously, said bell chamber means being maintained in equilibrium by the static part of the regulated pressure of one fluid acting thereon in opposition to the static part of the regulated pressure of the 30 other fluid, and means for applying a force of variable magnitude to said member, whereby the ratio existing between the pressure of the two fluids when the member is in equilibrium can be varied, and a constant 35 mixture of any desired strength thereby continuously obtained.

4. An apparatus for obtaining a constant mixture of two elastic fluids comprising in combination separate valves for regulating 40 the pressure of each fluid, a casing containing liquid, a member connected to said valves and situated within said casing so as to form an internal chamber sealed by the liquid therein, said member being subjected 45 internally to the static part of the regulated pressure of one fluid and externally to the static part of the regulated pressure of the second fluid, and means for applying a force to said member, whereby the ratio existing 50 between the internal and external pressures on said member when the latter is in equilibrium can be varied and a constant mixture of any desired strength continuously obtained.

5. An apparatus for obtaining a constant mixture of two elastic fluids which are supplied in separate conduits, comprising in combination a casing containing liquid, a member capable of angular movement with 55 in said casing, said member forming with the liquid in the casing a liquid sealed chamber, separate valves controlling the flow of the fluids in said conduits, branch conduits from each supply conduit on the outlet side

of said valves, one of the branch conduits 65 passing into the bell chamber and the other into the space above the liquid in the casing, whereby said member is subjected internally to the static pressure of one fluid, and externally to that of the other, and connecting 70 means between said member and each valve whereby the valves in being operated to keep the bell chamber member in equilibrium maintain a constant ratio between the pressures of the two fluids before mixing. 75

6. An apparatus for obtaining a constant mixture of two elastic fluids which are supplied from separate conduits, comprising in combination a casing containing liquid, a member capable of angular movement with 80 in said casing, and forming with said liquid a liquid sealed chamber, a regulating valve in each supply conduit, said valves being arranged to operate inversely with respect to one another, a branch conduit from 85 one fluid supply conduit on the outlet side of the valve therein to the chamber within said member, and another branch conduit from the outlet side of the regulating valve in the other conduit to the space above the 90 liquid in the casing whereby said member is subjected to the static pressure of the fluids acting in opposition to one another, and means connecting said member with each regulating valve, whereby the valves in being controlled by said member to keep the latter in equilibrium automatically maintain a constant ratio between the pressures of the two fluids before mixing. 95

7. An apparatus for obtaining a constant 100 mixture of two elastic fluids which are supplied by separate conduits, comprising in combination a casing containing liquid, a partition dividing the space above the liquid in the casing into two liquid sealed compartments, a member within each compartment 105 and forming with the liquid in the casing a liquid sealed bell chamber, a common shaft about which the two bell chambers thus formed are movable, valves connected 110 to said members and controlling the fluids in each conduit, means by which each member is internally subjected to the static pressure of the fluid to which the other member is externally subjected, said pressure being 115 that on the outlet side of the regulating valves, whereby the two bell chamber members in being maintained in equilibrium about said shaft by the static pressures of the two fluids, automatically operate the regulating valves to maintain constant the ratio between the pressures at which the two fluids are supplied. 120

8. An apparatus for obtaining a constant mixture of two elastic fluids which are supplied by separate conduits, comprising in combination a casing containing liquid, a partition dividing the space above the liquid 125

in the casing into two liquid sealed compartments, a member within each compartment and forming with the liquid in the casing a liquid sealed bell chamber, a common shaft about which the two bell chambers thus formed are movable, valves connected with said members and controlling the fluids in each conduit, means by which each member is internally subjected to the static pressure of the fluid to which the other member is externally subjected, said pressure being that on the outlet side of the regulating valves, whereby the two bell chamber members in being maintained in equilibrium about said shaft by the static pressures of two fluids, automatically operate the regulating valves to maintain constant the ratio between the pressures at which the two fluids are supplied, and means for varying the strength of the constant mixture of two fluids thus obtained.

9. An apparatus for obtaining a constant mixture of two elastic fluids and air which are supplied by separate conduits, comprising in combination a casing containing liquid, a partition dividing the space above said liquid into two liquid sealed compartments, a shaft mounted within said casing and situated parallel with the partition therein, two members rigidly connected together but capable of angular movement about said shaft, each member being situated within a separate compartment, and having an open interior forming with the liquid in the casing a liquid sealed chamber, separate valves controlling the flow of gas and air in their respective conduits, said valves being connected to the two bell chamber members, a branch conduit from the gas conduit on the outlet side of the gas controlling valve to the chamber within one of said members, a branch conduit from the air conduit on the outlet side of the air controlling valve to the space above the liquid in the compartment containing the member subjected internally to the gas pressure, two other similar branch conduits by which the other bell chamber member is internally subjected to the static pressure of the air in the air supply conduit and externally to that of the gas in the gas conduit, whereby the static pressures of the gas and air in being thus utilized to maintain the two bell chamber members in equilibrium automatically cause the latter to operate the gas and air controlling valves to maintain a constant ratio between the pres-

sures of the gas and air before mixing takes place.

10. An apparatus for obtaining a constant mixture of two elastic fluids comprising in combination a separate valve for regulating the pressure of each fluid, a member connected to said valves and operating the latter inversely with respect to one another, said member being maintained in equilibrium by the static part of the regulated pressure of one fluid acting in opposition thereto to the static part of the regulated pressure of the other fluid, means for applying a force to said member in order to vary the ratio existing between the pressure of the two fluids when said member is in equilibrium, a chamber in which said fluids mix after passing through the regulating valves and suitable valves for controlling the flow of fluid to said chamber, whereby a constant mixture of any desired strength is continually produced.

11. An apparatus for obtaining a constant mixture of two elastic fluids which are supplied in separate conduits comprising in combination a casing containing liquid, a partition dividing the space above said liquid into two liquid-sealed compartments, a member within each compartment and forming with the liquid in the casing a liquid-sealed bell chamber, a common shaft about which the two bell chambers thus formed are movable, valves connected to said members and controlling the fluid in each conduit means by which each member is internally subjected to the static pressure of the fluid to which the other member is externally subjected, said pressure being that on the outlet side of the regulating valves, a chamber in which the fluids mix after having passed through said valves, and means for regulating the flow of fluid into said mixing chamber whereby the two bell chamber members in being maintained in equilibrium about said shaft, by the static pressure of the two fluids automatically operate the regulating valves to maintain constant the ratio between the pressures of the fluids entering the mixing chamber.

In testimony whereof I have signed my name to this specification in the presence of two subscribing witnesses.
